(57) **CLAIM**

What is claimed is the ornamental design for a male quick-connect connector, as shown and described.

DESCRIPTION

FIG. 1 is a top front right perspective view showing the male quick-connect connector of Applicants' invention.

FIG. 2 is a top rear left perspective view of the male quick-connect connector of FIG. 1.

FIG. 3 is a top plan view of the male quick-connect connector of FIG. 1.

FIG. 4 is a front elevation view of the male quick-connect connector of FIG. 1.

FIG. 5 is a bottom plan view of the male quick-connect connector of FIG. 1.

FIG. 6 is a rear elevation view of the male quick-connect connector of FIG. 1.

FIG. 7 is a left side elevation view of the male quick-connect connector of FIG. 1; and,

FIG. 8 is a right side elevation view of the male quick-connect connector of FIG. 1.

The broken lines in the figures are used to represent subject matter that forms no part of the claimed design.
